UNITED STATES PATENT OFFICE.

CLARENCE C. CRALEY, OF HARRISBURG, PENNSYLVANIA.

METAL-WORKING MACHINERY.

1,007,185.

Specification of Letters Patent. Patented Oct. 31, 1911.

Application filed May 9, 1911. Serial No. 626,030.

To all whom it may concern:

Be it known that I, CLARENCE C. CRALEY, a citizen of the United States, residing at Harrisburg, in the county of Dauphin and 5 State of Pennsylvania, have invented new and useful Improvements in Metal-Working Machinery, of which the following is a specification.

The present invention relates to metal 10 working machinery, in which great accuracy is necessary, and the object is to provide a simple and practicable means for rapidly and accurately laying out, machining and inspecting tools and the like, such as jigs, master plates, templets, dies, etc. Heretofore work of this character, which requires the utmost precision, has been accomplished to a great extent through experimenting, thus requiring not only a great 15 amount of time, but very often resulting in inaccurate work, which can only be determined by inspection.

It is the primary object of the present device to provide simple mechanism by which 20 the accuracy of the work can be determined with exactitude at the time it is laid out and performed. Furthermore it can be accomplished with expedition and without mere 25 experimenting.

A simple embodiment of the invention is 30 illustrated in the accompanying drawings, wherein:

Figure 1 is a side elevation in a conventional manner of a machine having the novel 35 mechanism. Fig. 2 is a detail view on an enlarged scale, showing the gaging structure. Fig. 3 is a longitudinal sectional view on the line 3—3 of Fig. 2. Figs. 4, 5 and 6 are respectively cross sectional views on the 40 lines 4—4, 5—5 and 6—6 of Fig. 2.

Similar reference numerals designate corresponding parts in all the figures of the drawings.

In the embodiment illustrated, a drill 45 press is disclosed, and includes a work supporting table, in which a rotatable member 7 carries a transversely slidable member 8 on which is mounted another sliding member 9 that moves at right angles to the member 8. Suitable means 10 are provided for effecting the movements of the members 8 and 9. As thus far described, the structure is well known, and may be varied to a considerable degree. Each set of members 7 and 8 and 9 are provided with means for 50 gaging the amount of movement that may

be given to them, and these gaging means permits a great amount of movement, while indicating such amount of movement to an exceedingly small degree, as for instance, the 60 thousandth of an inch.

Inasmuch as the gaging mechanisms for both sets of members are the same, a description of one is believed to be sufficient for both, and one of the same in detail is illustrated in Figs. 2-6 inclusive. Thus in Fig. 2, the member 8 may be considered as the supporting member, and the member 9 as the work-carrying member. Said member 9 is provided with a longitudinal substantially T-shaped slot 11, formed in an overhanging portion of the member 9, as will be clear by reference to Fig. 4. In this slot is located the head 12 of a securing bolt 13, which bolt supports a bracket 14 that can thus be moved to different positions on the member 9 and fixed at such positions. The bracket 14 is provided with a socket 15, in which is slidably mounted a stop head 16 having a stem 17 that projects through the 80 rear side of the bracket where it is threaded to receive an adjusting nut 18. A spring 19, interposed between the head 16 and the rear wall of the socket, serves to urge said head to projecting relation. The lower corner 85 of the bracket is split, as shown at 20, and one or more binding screws 21 are passed therethrough. With this arrangement, it will be evident that if the screws 21 are loosened, the head may be positioned with 90 respect to the bracket 14, as desired, and when the desired position has been obtained by setting the screws 21, the head will be fixed against accidental movement. The supporting member 8 is also provided with 95 a suitable bracket 22 that carries a micrometer head 23. This head may be of any well known form, and includes an adjustable stem 24 that cooperates with the end of the stop head 16. The bracket 14 is provided with an arm 25 having an upturned end 26, in which is formed a V-shaped seat 27. Pivoted to the other bracket 22 is another arm 28 having an upturned end 29 provided with a V-shaped seat 30. A retaining spring 100 31 extends over this seat. The pivotal mounting of the arm 28 is shown at 32, and it will be noted that in the form of construction shown, and as illustrated especially in Fig. 3, the outer corner 33 of the arm 28 is square and is borne against by a spring 34 secured to the bracket 22. 105 110

In using the mechanism, the work is first clamped upon the member 9 in the desired position, and the gage elements, comprising the micrometer head 23 and the stop head 16, are placed in associated position, and are arranged in the desired relation. Assuming that holes are to be drilled at predetermined distances apart, after the first hole has been made, the member 9 is moved the desired distance, and simultaneously with this movement, the micrometer head is also operated, so that the distance in one direction can be determined with the greatest accuracy. If necessary, the members 8 and 9 together may be moved transversely of the member 7, and in like manner, the position can be determined by the gaging mechanism employed between these two members. If the distance is so great that the micrometer head 24 will be carried out of coaction with the stop head 16, spacing devices, in the form of pins 35, of predetermined standard lengths, may be interposed between said stem and head, as illustrated in Fig. 2. For example, pins of one, two, three inches, etc. may be employed. The pin desired is placed in the seats 27 and 30, and is retained by the spring 31. When the pin is not employed, it will be evident that in the structure shown, the arms 25 and 28 may interfere, but inasmuch as the arm 28 is pivotally mounted, it can be swung to the position illustrated in dotted lines in Fig. 3, whereupon the parts 24 and 16 can be brought into operative position, and the stem 24 can pass freely through the seat 27 of the arm 25. When in position, the pin 35 has a free sliding movement in the seats, so that it will adjust itself to proper position. As already explained, this gaging mechanism can be employed on either or both of the sets of members 7 and 8 and 8 and 9. In the claims therefore, the term "work-carrying means" is intended to be broad enough to cover the parts 8 and 9 when they move together with respect to the member 7, and in like manner the term "supporting member" is intended to be broad enough to include the member 8 when the member 9 *per se* acts as the work-carrying member, and is moved with respect to the member 8.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention. For example, the handle or micrometer head may be placed on either side to suit the convenience of the operator, and the micrometer 55 may be graduated so that a finer adjustment

than one thousandth of an inch can be read. Furthermore the device may be employed on other machines besides drills, as will be obvious to those skilled in the art.

Having thus fully described my invention, 70 what I claim as new, and desire to secure by Letters Patent, is:—

1. In a machine of the character set forth, the combination with a supporting member, of a work carrying member movably mounted thereon, means for moving the carrying member on the supporting member, one of the members having a substantially T-shaped slot, and indicating means including a stop having securing means longitudinally 75 adjustable in the slot, and a gage element movably mounted on the other member and coacting with the stop.

2. In a machine of the character set forth, the combination with a supporting member, 85 of a work carrying member movably mounted thereon, means for moving the carrying member on the supporting member, a stop element mounted on one member and comprising a securing device, and a head adjustably mounted thereon, and a gage element 90 movably mounted on the other member and coacting with the stop.

3. In a machine of the character set forth, the combination with a supporting member, 95 of a work carrying member movably mounted thereon, means for moving the carrying member on the supporting member, a stop element mounted on one member and comprising a securing device, a head slidably 100 mounted thereon, and means for holding the head in different positions, and a gage element movably mounted on the other member and coacting with the head.

4. In a machine of the character set forth, 105 the combination with a supporting member, of a work carrying member movably mounted thereon, means for moving the carrying member on the supporting member, one of said members having a substantially T-shaped slot, a bracket having securing means 110 adjustably mounted on the slot, a head slidably mounted in the bracket, a spring for projecting the head, a nut for holding the head against movement by the 115 spring, clamping means for said head, and a micrometer head movably mounted on the other member and co-operating with the head.

5. In a machine of the character set forth, 120 the combination with relatively movable supporting and work-carrying members, of coacting gage elements carried respectively thereby, a spacing element arranged to be detachably interposed between the gage elements, and means for supporting the spacing element, when so interposed.

6. In a machine of the character set forth, 130 the combination with relatively movable supporting and work carrying members, of

- coacting gage elements carried respectively thereby, a spacing element arranged to be detachably interposed between the gage elements, and spaced supports for the spacing elements when so interposed, said supports having seats for said spacing elements.
7. In a machine of the character set forth, the combination with relatively movable supporting and work-carrying members, of coacting gage elements carried respectively thereby, a spacing element arranged to be detachably interposed between the gage elements, and means for supporting the spacing element when so interposed, said means having a retaining device for said spacing element.
8. In a machine of the character set forth, the combination with relatively movable supporting and work-carrying members, of coacting gage elements carried respectively thereby, a spacing element arranged to be detachably interposed between the gage elements, means for supporting the spacing element when so interposed, said means having a seat for receiving the said spacing element, and a spring retaining device that extends over the seat.
9. In a machine of the character set forth, the combination with relatively movable supporting and work-carrying members, of coacting gage elements carried respectively thereby, a spacing element arranged to be detachably interposed between the gage elements, and means movable to and from a position between the gage elements for supporting the spacing element when so interposed.
10. In a machine of the character set forth, the combination with relatively movable supporting and work-carrying members, of coacting gage elements carried respectively thereby, a spacing element arranged to be detachably interposed between the gage elements, and means pivotally mounted on one of the members and movable to and from a position between the gage elements for supporting the spacing element when so interposed, said supports having seats for said spacing elements.
11. In a machine of the character set forth, the combination with relatively movable supporting and work-carrying members, of coacting gage elements carried respectively thereby, a spacing element arranged to be detachably interposed between the gage elements, a supporting bracket for the spacing element mounted on one of the members and movable to and from a position between the gage elements, and means for holding the supporting bracket both in and out of its position between the gage elements.
12. In a machine of the character set forth, the combination with a supporting member, of a work-carrying member movably mounted thereon, means for moving the work-carrying member on the supporting member, one of said members having a substantially T-shaped slot, a bracket having fastening means adjustably mounted in the slot, a stop head adjustably mounted on the bracket, a support carried by the other member, a micrometer head mounted on the support and coacting with the stop head, a spacing element arranged to be interposed between the stop head and micrometer head, and spaced supports for the spacing element, one of said supports being pivotally mounted, and a spring for holding said pivotally mounted support in different positions.
